UNITED STATES PATENT OFFICE

FRANK L. BAMFORD, OF DETROIT, MICHIGAN, ASSIGNOR TO C. M. HALL LAMP COMPANY, OF DETROIT, MICHIGAN, A CORPORATION OF MICHIGAN

FOCUS-ADJUSTMENT MECHANISM FOR LAMPS

Application filed September 30, 1925. Serial No. 59,660.

The invention relates to vehicle head lights of that type in which the illumination is alternatively supplied by a pair of filaments in the same bulb and off-set one from the other. 5 Such constructions are designed to illuminate the road which is in the immediate foreground with the filament which is in the lower plane and greater distance with the filament in the higher plane, but to accomplish this 10 each filament must be positioned with great accuracy with respect to the axis of the reflector. There must also be provision for adjusting the filaments axially of the reflector for proper focusing.

15 It is the object of the present invention to obtain a simple construction of adjusting mechanism for effecting both the focus and the lateral adjustment of the lamp.

It is a further object to avoid any loose connection which might cause a rattling or vibration of the lamp when in instant service.

With these objects in view the invention consists in the construction as hereinafter set forth;

25 In the drawings;

Figure 1 is a central longitudinal section through a lamp to which my improvements are applied.

Figure 2 is a section on the line 2—2 of 30 Figure 1.

Figure 3 is a section on the line 3—3 of Figure 4.

Figure 4 is a front elevation of the bushing as attached to the reflector.

35 Figure 5 is a perspective view of the bushing.

A is a lamp casing of any suitable form and B is the reflector mounted therein. C is the bulb which is provided with a pair of filaments D, D' arranged in parallel planes respectively above and below the central axis. The lamp bulb is mounted in a socket member E which extends through a central aperture in the reflector and is provided with a rearwardly extending shank F. This shank is engaged by a screw G passing through a slot in the rear wall of the casing A with its head H outside of said casing. There is also a spring I arranged intermediate the casing 45 and the rear end of the shank F which forces

the socket forward to the position permitted by the adjustment of the screw.

The construction as thus far described has been heretofore used and provides for the adjustment of the bulb axially of the reflector for the purpose of focusing. It does not, however, accurately position the filaments with respect to the lateral distance from the central axis which function is performed by the following construction:

J is a bushing member arranged within the aperture in the reflector and slidably receiving the socket member E. This bushing is pivotally attached to the reflector preferably by providing the struck out lugs K, K' on diametrically opposite sides thereof which engage recesses L, L' in the reflector B and in the horizontal and axial plane thereof and a spring M in a sleeve upon the bushing its rear end engaging a flange N thereon and its forward end abutting against the rear face of the reflector. Thus the lugs K, K' engaging the recesses L, L' form rocker bearings or pivots for the bushing while the spring M holds these parts in engagement yieldably 60 centering the bushing and preventing any rattle. To permit of assembling the parts, the reflector is apertured at O and O' for the passage of the lugs K, K' therethrough from the rear of the reflector, the spring M being 65 compressed after which the bushing is revolved to a quarter revolution to engage said lugs with the recesses L and L'.

The pivotal connection between the bushing and the reflector just described permits 70 of rocking said bushing and the lamp socket contained therein so as to tilt the bulb downward or upward within the reflector. To permit of this movement the screw G which connects the shank F with the rear of the casing A is adjustable in the vertical slot F'. I also 75 preferably provide an adjusting mechanism which, as shown, comprises a sliding bar P lying adjacent to the rear wall of the casing and apertured for the passage of the screw G. This slide also forms the abutment for the rear end of the spring I so that by movement 80 of the slide the screw, spring and shank F will be carried therewith thereby effecting 85 rocking of the socket and lamp bulb. To 90

50 55 60 65 70 75 80 85 90 95 100

actuate the slide P there is provided a cam or eccentric Q which engages the bearing R, R' on the slide and this is actuated by a rotary shank S having a slotted head on the outside of the rear wall of the casing, said shank having a polygonal portion for engaging the cam which is surrounded by a spring S' abutting against a collar U secured by a cotter pin U'. This forms a simple construction to manufacture and assemble 10 and one which is free from rattles.

With the construction as described, to adjust the focus of the lamp, the head H of the screw G is turned to move the lamp socket and bulb inward or outward along the axis 15 of the reflector. To adjust the lamp for proper positioning of its lamps with respect to the axis of the reflector, the head of the shank F is turned which, by actuating the cam or eccentric Q will move the slide P carrying with it the screw G, spring I and shank F. It is, therefore, possible to quickly 20 and easily adjust these filaments so as to secure the desired lighting effect when each filament is illuminated.

What I claim as my invention is:

1. In a lamp, the combination with a reflector, a lamp bulb and a socket therefor passing through an aperture in said reflector, 30 of a bushing for slidably receiving said socket pivotally engaging said reflector, resilient means sleeved on said bushing and engaging said reflector for yieldably holding said bushing from movement on its pivots, 35 and adjusting means for rocking said bushing to adjust said lamp bulb transversely with respect to the axis of the reflector.

2. In a lamp, the combination with a reflector, and a lamp socket extending through 40 an aperture therein, of a bushing in which said socket is slidably secured also passing through the aperture in said reflector and provided with diametrically opposite rocker bearings in an axial plane engaging co- 45 operating recessed bearings in said reflector, resilient means for holding said bearings in engagement with each other and preventing rattling and means for rocking said socket and bushing.

3. In a lamp the combination with a reflector, of a lamp socket extending through an aperture therein, means for adjusting said lamp socket axially, a bushing in which said socket is slidably secured also passing through 55 said aperture in the reflector, said bushing being provided with diametrically opposite projecting lugs for rockably engaging recessed bearings in said reflector, a spring sleeved on said bushing bearing at its forward end against the rear face of the reflector and a flanged bearing on said bushing against which the opposite end of said spring abuts.

4. In a lamp, the combination with a reflector, of a lamp socket passing through an 60 aperture therein, a bushing in which said

socket is slidably secured also passing through the aperture in the reflector, said bushing having a radially outwardly extending flange at its rear end and being provided with struck out lugs on diametrically opposite sides thereof and at its forward end, said reflector being provided with slots for the passage of said lugs therethrough and with recessed bearings for engaging said lugs when said socket is given a partial revolution, and a 75 spring sleeved on said socket bearing at its rear end against said flange and at its forward end against the rear face of the reflector.

5. In a lamp the combination with a reflector, of a lamp socket extending through an aperture therein and provided with a rearwardly extending shank, means operable from outside the casing for adjusting said shank and socket axially of the reflector, a bushing in which said socket is slidably secured extending through and pivotally engaging the face of the said reflector, means for yieldably maintaining the pivotal engagement of said bushing with said reflector and means operable from outside the lamp casing for adjusting said shank transversely of the axis of the reflector to rock said socket and bushing about said pivot.

6. In a lamp, the combination with a reflector, of a lamp socket passing through an aperture therein and provided with a rearwardly extending shank, a screw for engaging said shank passing through an aperture in the rear wall of the casing and provided with an operating head outside the casing, a bushing in which said socket is slidably secured pivotally engaging said reflector, a slide within said casing engaging said screw and means operable from outside the casing for adjusting said slide and through the medium of said screw and shank rocking said socket and bushing.

7. In a lamp, the combination with a reflector, a lamp bulb and a socket therefor passing through an aperture in said reflector, of a bushing for slidably receiving said socket pivotally engaging said reflector, means for yieldably holding said bushing free from movement on its pivots and for maintaining the pivotal engagement of the bushing with the reflector and adjusting means for rocking said bushing to adjust said lamp bulb transversely with respect to the axis of the reflector.

8. In a lamp, the combination with a reflector, of a lamp socket pivotally engaging said reflector, and provided with a rearwardly extending shank, means passing through a slot in the rear wall of the casing and engaging said shank for adjusting the same and said socket axially, a slide inside said casing adjacent to the rear wall thereof engaging said adjusting means, a cam member for actuating said slide to rock said socket on its 125

pivot, and means operable from outside the casing for actuating said cam.

9. In a lamp, the combination with a reflector, of a lamp socket passing through an aperture therein and provided with a rearwardly extending shank, a bushing in which said socket is slidably secured pivotally engaging said reflector, a screw passing through a slot in the rear wall of the casing and engaging said shank to adjust the same axially of the reflector, a slide inside said casing adjacent to the rear wall thereof engaging said screw, a spring surrounding said screw bearing against said slide and said shank, a cam for engaging said slide to actuate the same, and a rotary shank for said cam passing through the rear wall of the casing and operable to rock said bushing and socket.

10. In a lamp, the combination with a housing and a reflector therein, of a lamp socket rockably mounted within said housing, a slide for rocking said socket, a cam for actuating said slide and a shank for actuating said cam, said shank having a slotted head outside said housing, a polygonal portion within said housing engaging said cam, a spring sleeved on said polygonal portion for exerting a resilient pressure on said cam to prevent rattling of the same, a collar on said shank forming abutment for said spring and a cotter pin for retaining said collar on the shank.

11. In a lamp, the combination with a casing, of a reflector within the casing, the said reflector being provided with an aperture, a lamp socket, means for pivotally and slidably mounting the lamp socket in the aperture in the reflector, a shank extending rearwardly from the lamp socket, means passing through a slot in the rear wall of the casing and engaging said shank for adjusting the socket axially, resilient means for urging the said shank and socket forwardly, and a slide within the casing and engaging the said adjusting means for rocking the said adjusting means, shank, and lamp socket.

In testimony whereof I affix my signature.
FRANK L. BAMFORD.
